ALDEN HUDSON, OF GREEN BAY, WISCONSIN, ASSIGNOR TO DAVID WILLIAM HUDSON, OF GREEN BAY, WISCONSIN.

MACHINE FOR THE MANUFACTURE OF PAPER ARTICLES.

Application filed January 14, 1924. Serial No. 685,987.

This invention relates to improvements in machines for the manufacture of paper articles. More particularly, this invention relates to a machine which is peculiarly adapted for making napkins, toilet paper and the like, but which may be used for the purpose of making other articles embodying sheets of paper or other flexible substances.

It is the primary object of this invention to provide a novel and simple machine which will be susceptible of adjustment to cut and fold sheets of varying sizes. It has heretofore been the practice to provide a separate machine for each size of folded article to be produced. This practice has necessitated large investments in machinery of this character as well as large areas of floor space to accommodate such machines. The disadvantages of the fixed type of machine are obvious and, in the case of a small industry, are serious. The present invention contemplates the provision of a machine which can be adjusted to produce, within certain limits, any desired size or shape of folded paper article, and therefore it is adapted to overcome the objections noted above.

A further very important object of this invention consists in the arrangement by which adjustments are made for the manufacture of different sizes of folded paper articles. It will be understood that a machine of this type involves a considerable number of parts to act on the paper, and it is necessary that such parts be actuated in synchronism. Therefore, a change of adjustment as to the operation of one of such parts will usually require a corresponding change in adjustment to control others of said parts, and it is one of the objects of this invention to provide means for controlling simultaneously adjustments of a plurality of synchronously operated parts so that the independent adjustment of each of such parts will be unnecessary.

It is also an important object of this invention to provide means for producing in an article, such as a napkin or the like, a fold at a point which is not fixed intermediate the ends of a napkin but may be adjusted within limits to the end that the napkin fold may be disposed exactly between the ends of the napkin or may be disposed at points offset from the center line thereof.

Other objects of this invention are to pro-

vide a simple, compact construction for the purposes aforesaid; to provide a machine 55 easily susceptible of adjustment and easily operated; to provide a machine having a novel type of paper shearing mechanism which is particularly adapted for association with the folding mechanism of an adjustable 60 machine; to provide a type of machine which consists of a plurality of units adapted to act simultaneously upon a corresponding number of webs of paper and all controlled by the same driving and adjusting mechanism 65 to produce simultaneously napkins of a given size and having a given location of fold.

The drawings are largely diagrammatic but are intended to show in general the relative sizes of the parts as well as their respective location.

In the drawings:

Figure 1 is a diagrammatic side elevation of a device embodying the invention to which this application is directed.

Figure 2 is an end elevation of the device shown in Figure 1.

Figure 3 is a plan view of the majority of the working parts of the device, the superstructure being cut away substantially to the section indicated at 3-3 in Figure 2.

Figure 4 is a view of the driving and interconnecting gear as it appears from the rear of the machine.

Figure 5 is a detail view in front elevation 85 of a crank disk.

Figure 6 is a view similar to Figure 5, of a disk with which disk the disk shown in Figure 5 co-operates.

Figure 7 is a vertical axial section through 90 the assembled disks shown in Figures 5 and 6.

Figure 8 is a view similar to Figure 1, showing one sheet passing through the folding rolls and a new length of web being fed into the machine.

Figure 9 is a view similar to Figure 8, showing a deflector acting on the infed portion of the web, and showing the tucking blade fully retracted.

Figure 10 shows the tucking blade commencing to act upon the web.

Figure 11 is a detail view taken on the section indicated at 11-11 in Figure 10.

Figure 12 is a sectional view on an enlarged scale of the paper severing mechanism taken 105 on the line 12-12 of Figure 3.

Like parts are identified by the same reference characters throughout the several views.

The frame work of the machine is indicated in its entirety by the reference character 1. Paper webs 2 are fed into the machine from supply rolls 3 and pass about the guide rolls 4 from which they extend downwardly through the folding devices 5. Such devices are well known in the art and are adapted to 10 put any desired number of longitudinal accordion folds in a moving web of paper or other flexible material. These devices are retained in place through the medium of gravity actuated links 6, whereby they may readily be removed for the substitution of other similar devices adapted to produce a different number of folds.

The longitudinally folded webs, one of which appears at 7 in Figure 1, are led downwardly between feed rollers 8 and 9. As is clearly shown in Figure 2, there are two of such rollers in axial alignment for the two parts of the machine. Each of the rolls 8 is mounted on a shaft 10 which comprises 25 the primary drive shaft of the machine and, for power receiving purposes, carries a pulley 11. Similarly, each of the rollers 9 is mounted on a shaft 12 which is parallel to shaft 10 and is connected thereto through the medium 30 of gears 13 and 14, respectively (see Figure 3).

Extending between the uprights of frame 1 are the bridge members 15 which may be integrally connected by means of bearing members 16 providing a pair of parallel dove-tailed channels within which the slides 17 are operable. These slides are preferably accurately fitted to their respective bearing members inasmuch as each slide carries a shearing knife. In order to maintain the slides operative despite any wear which may occur in the use of the machine, each slide may rest on one side upon a take-up member 18 which is adjustable centrally of its slide by means 45 of a set screw 19. The take-up member 18 will conform in angularity to the dove-tailed portion of the slide, and consequently, will act like a wedge to keep the slide pressed against the retaining or cover plate 20.

To facilitate an understanding of the operation of the device, a portion of the cover plate 20 is shown in broken lines in Figure 1. Immediately beneath each pair of feed rolls 8 and 9 the cover plate is provided with 50 an aperture or transverse slot 21 which will preferably have square cut margins between which the longitudinally folded web 7 will be fed. To ensure that the web will be guided through slot 21, I preferably provide the 55 standing fingers 22 and 23 which are spaced apart at substantially the width of the slot and are received into suitable peripheral grooves 24 in the feed rolls. This arrangement makes it impossible for the web to follow the rolls through adherence.

The slide 17 carries a transverse shearing bar 25 which, for clearness, is shown in section in Figure 1, although Figure 1 is primarily a side elevation. Due to the angular position of the take-up gibs 18, the slide 70 will be maintained with shear bar 25 in a position to co-operate with the square cut margins of slot 21. The slide 17 and shear bar 25 are reciprocable through means hereinafter to be described and, in each direction of reciprocation of the shear bar 25, it will co-operate with one margin of slot 21 to sever the web portion projecting therethrough. In the position of the parts illustrated in Figure 1, this severing operation is just occurring and, for 80 purposes of illustration, the shear bar 25 may be considered to be moving in the direction indicated by the arrow immediately beneath it.

Disregarding for the moment the portion 85 of the web which has just been severed by the shear bar, the newly infed web portion will be considered from the time of its arrival through slot 21 until it is discharged from the machine. Thus a complete cycle of 90 operation will be described.

After severing the web, shear bar 25 will move to the position in which it is indicated in Figure 8, and simultaneously the rotation of rolls 8 and 9 will advance web 7 until its end contacts with the deflector 27. This deflector may be stationary but will preferably be mounted for oscillation upon a cross shaft 28 and will, through actuating mechanism hereinafter to be described, be oscillating at 100 this point of the cycle in a clockwise direction. It is the function of the deflector 27 to prevent the advancing end of the web from adhering to the extremity of the preceding napkin, or may otherwise be caught between 105 the folding rollers 29 and 30.

The tucking blade 31 which, in the positions of the parts shown in Figures 1 and 8 is in the path of the advancing web, is being retracted at this time in the direction indicated by the arrow in Figure 8 and eventually reaches the position in which it appears in Figure 9. At this point the shear knife 25 is practically at the end of its stroke, and the tucking blade 31 is also almost fully retracted. 110 The end of the longitudinally folded web portion 7 has now been fed by feed rolls 8 and 9 onto a transverse series of belts 32. These belts pass over spaced pulleys 33 and 34 upon shafts 35 and 36, respectively. A sufficient 115 number of belts is employed to provide adequate support for the end of the advancing web. These belts advance in the direction indicated by the arrows, either at the speed of web advance or at a slightly greater speed, 120 so that they assist in maintaining the web in position and under that slight degree of tension which is desirable for the most perfect 125 operation of the machine.

Co-operating with belts 32 are belts 37 130

which are disposed above the path of the advancing web and are carried by upper and lower pulleys 38 and 39 mounted respectively on shafts 40 and 41. The size and location of pulleys 39 is such that these pulleys will be disposed in staggered relation with pulleys 34, and a belt 37 will lie between each pair of belts 32. This arrangement is such as to ensure frictional contact of both belts with the web so that by the time the web reaches the position in which it appears in Figure 10 the extremity of the web will be corrugated to lie between belts 32 and 37 and pulleys 34 and 39.

When the web reaches the point in its advance in which it is shown in Figure 10, the tucking blade will be well advanced on its operating stroke and will be engaged with the paper, as indicated in Figure 10, while moving in the direction of the arrow in said figure. The engagement of the belts 32 and 37 with the paper will hold it under tension at the time of contact of the tucking blade therewith, and will thereby ensure a perfect fold on a line normal to the margins of the web.

If the sheet is not so held the fold will not always be straight. The upper belt 37 also serves to prevent the sheet or web from snapping backward. The shearing knife 25 will also be on its return stroke and will be approaching rapidity to the point where it will again sever that portion of the web with which the tucking blade 31 is engaged. The fact that the web is unsevered at this time ensures that it will be under tension, due to the pull of the belts thereon.

As the parts continue to move they will complete the cycle by reaching the positions in which they appear in Figure 1. The tucking blade 31 will force an intermediate portion of the web between the folding rolls 29 and 30 which will act upon the web in the usual manner, first to crease the fold made by the tucking blade and then to draw the severed portion of the web between themselves in the form of a completed paper article. The shearing knife 25 will be so synchronized with the movements of the tucking blade that the shear knife will sever the web substantially exactly at the time when the portion to be severed is forced by the tucking blade into the operative grip of folding rolls or vise rolls 29 and 30.

As the cycle just described recommences, the severed napkin is directed by roller 55 into a trough 141 down which it slides until it reaches a point of registry with chute 42. At this point it is brought to rest by means of a suitable stop 43. At this point the packer 45, which is mounted on rock shaft 46 and is in course of retraction in Figures 1 and 8, moves downwardly as indicated by the arrows in Figures 9 and 10 until it contacts with the newly formed folded article and compresses it above previously formed articles in the chute 42. Thus, upon each of the active

strokes of the packer the articles in the chute will be advanced for a distance equivalent to the thickness of the newly added article.

The operation of the machine in general has been described before its specific mechanical connections were set forth in order that the adjustable features of the machine might be the more fully appreciated. It will be understood from the foregoing that it is necessary that the shear knife 25, tucking blade 31, the oscillatory deflector 27, and the packer 45 must all operate upon the work with synchronized action, and their operation must also be synchronized with the rate of advance of the web by the feed rolls 8 and 9. Furthermore, it will also be appreciated that for special work it is desirable to provide for the independent adjustment of several of these mechanical elements to change their time of action with respect to the action of others of the elements. It is also desirable, however, to provide for the simultaneous adjustment of the relative time of action of a plurality of elements when simultaneous adjustment is possible consistent with the desired operation of the machine. One set of mechanical connections for accomplishing the results expressed immediately above will now be described, but inasmuch as it is obviously a simple matter to design equivalent means for obtaining this result I do not desire to limit myself to the specific construction herein disclosed, except as specifically pointed out hereinafter in the claims.

As has already been stated, power is applied to the machine through pulley 11 which is mounted on shaft 10. Gears 14 and 13 on shafts 10 and 12, respectively, connect such shafts for simultaneous rotation. From gear 13 power is transmitted not only to shaft 12 but also to a transmission gear 47 which may be mounted on a stud shaft 47' carried by the frame 1. Gear 47 meshes at the back of the machine with a gear 48 on the shaft 49 which carries one of the folding or vise rolls 29. This gear 48 meshes in turn with a gear 50 on shaft 51 which carries the other folding or vise roll 30. Thus, the rotation of both of the vise rolls is provided for, and it will be noticed that no adjustment is necessary to control the relative rates of rotation on such rolls. Due to the reduction gearing employed between drive shaft 10 and the shafts 49 and 51, these shafts and the vise rolls 29 and 30 carried thereby will always rotate at relatively high speeds, and will thereby be adapted to handle any length of napkin which can be fed to them by the feed rolls 8 and 9. With respect to the feeding rolls 8 and 9, the speed of the clamping rolls 29 and 30 is constant.

The shaft 51 which carries the vise roll 30 is driven by gear 50 at its rear end and at its forward end it carries a gear 52, which is shown in dotted lines in Figure 4, by reason

of the fact that it is at the front of the machine. Gear 52 meshes with a gear 53 which is likewise at the front of the machine and is carried by a shaft 54 upon which the rotary 5 deflecting roller 55 is mounted.

The shafts 35 and 40, carrying respectively pulleys 33 and 38, are interconnected by means of intermeshing gears 57 and 58 on shafts 41 and 36, and by the belts 32 and 37 10 already described. These shafts are both driven through a gear 59 disposed centrally on shaft 35 which meshes with ring gear 50' on the vise roll 30. Thus, the belts 32 and 37 and the rotary deflector 55, as well as the 15 vise rolls 29 and 30, are all driven at constant speed with reference to the feed rolls 8 and 9, inasmuch as it is unnecessary to change the relative speed of movement.

As best shown in Figure 3, the two driving 20 rolls 9 on shaft 12 are axially spaced apart to receive between them a gear 60 which, if the rolls 9 are integrally connected, may comprise a ring gear. The rolls 8 which are illustrated in Figure 3 as being integrally constructed 25 are grooved at 60' to provide clearance for gear 60. The groove 60' lies between and defines the independent rolls 8 which act upon different webs of paper. Meshing with gear 60 is an intermediate gear 61 adjustably supported 30 on a stud 62 in the end of an arm 63 on a rock shaft 64. The rock shaft may be constructed in any desired manner to be supported in any adjustment with reference to the frame. For example, it may, as indicated 35 in dotted lines in Figure 1, be provided with an arm 65 substantially at right angles to arm 63 and provided with a slotted head 66 which may be secured in any position of oscillatory adjustment by means of a set screw 67 40 in threaded engagement with the frame. There is also a slot in arm 63 at 68 to permit the adjustment of stud shaft 62 radially of arm 63, whereby to maintain gear 61 in mesh despite the oscillatory adjustment of rock 45 shaft 64 and arms 63 and 65.

Journaled in the frame 1 is a cross shaft 70 upon which are slidably mounted a series of gears 71, 72, and 73 which may either be splined to the shaft or may be provided with 50 set screws 74 for securing them in any desired position of adjustment thereon. The arrangement is such that any of the gears just described can be positioned selectively upon the shaft in the plane of intermediate gear 61 55 to receive motion therefrom. The adjustment of rock shaft 64 and arm 63 which carry gear 61 are intended and adapted to permit gear 61 to be moved into mesh simultaneously with its driving gear 60 and its driven gears 60 71, 72, or 73. While only three gears have been illustrated on shaft 70, it will be obvious that the number of gears on said shaft could be multiplied indefinitely to produce any desired 65 relative speed between said shaft and the driving gear 60 on shaft 12.

Keyed to shaft 70 at its ends are the disks 75 and 76 located respective at the front and back of the machine. One of these disks is illustrated in elevation in Figure 6 and in section in Figure 7. The disks are each apertured at 78 to receive threaded bolts 77. Co-operating with disks 75, 76 are disks 80 having arcuate slots 81 to receive bolts 77 and carrying crank pins 82 and 82'', respectively. Thus, the arrangement is such that 75 each crank pin is rotatably adjustable with reference to the shaft 70 with which it is connected for operation. The adjustment of the crank pins provides for the independent timing of the members driven through shaft 70, 80 whereas the several gears 71, etc., on shaft 70 permit of the simultaneous adjustment for timing purposes of all elements driven through said shaft.

The crank pin 82 connected with shaft 70 85 at the rear of the machine receives a connecting rod 83, whereby it is joined to a rocker arm 84 on the rock shaft 85 which carries the tucker 31. The rotative movement of shaft 70 is thus transmitted to rock shaft 85 to produce oscillation of said shaft and the corresponding movement of the tucker as previously described.

At the front of the machine, and preferably exterior to the frame thereof, shaft 85 95 carries a cam 105 which actuates a roller cam follower 106 on the reciprocable link 107. This link is connected at 108 with an arm 109 on rock shaft 28 which carries the deflector 27. A spring 110 presses link 107 downwardly to maintain cam follower 106 in operative contact with cam 105. The link 107 may be guided in any suitable means, such as the spaced rollers 111 and 112 connected 100 with the frame of the machine. A retaining member 113 mounted on the axle studs of roller 111 and 112 maintains the link in operative position between the rollers.

The crank pin 82'' at the front of the machine actuates a connecting rod 86 which is 110 engaged with arm 87 on the rock shaft 46 which supports the packer 45. Therefore, the rotative movement of shaft 70 produces the above described oscillations of the packer and such oscillations are not only adjustable 115 simultaneously with the adjustment of the tucking blade but are also adjustable independently thereof through the medium of the adjustable crank pin support through which each of the connecting rods 83 and 86 is independently operated.

Reference has already been made to the gear 14 on driving shaft 10 through which all of the above described gearing and motion transmitting connections are operated. This gear also actuates a further line of power transmitting mechanism, including a gear 90 adjustably mounted on a stud shaft 125 gear 90 adjustably mounted on a stud shaft 91 which is carried in an arcuate slot 92 in the frame, the slot being concentric with the 130

axis of shaft 10. Thus, while the shaft 91 is adjustable, the gear 90 carried thereby will always mesh with gear 14 to be driven therefrom.

5 A cross shaft 94 in the frame is adapted to carry interchangeably at its rear end any one of a series of any desired number of gears, of which the gear 95 is one. This gear is held in place by means of a nut 96 on the end of 10 shaft 94 or by any other equivalent means adapted to permit of the ready removal of the gear 95 for the substitution of another gear of different size. This arrangement constitutes a well known type of change speed 15 mechanism embodying change speed gearing of the so called "take-off" variety. Other change speed mechanism might be employed, but inasmuch as there are ordinarily few 20 changes or adjustments in a machine of this character no complicated change speed gearing would be warranted, and that illustrated has the advantage of being extremely simple and easy to operate.

Opposite to the end of shaft 94 which 25 carries gear 95 is a disk 75' and a complementary disk 80' corresponding to disks 75 and 80 previously described. Disk 80' carries a crank pin 82' which is connected by pitman 97 with the rocker arm 98 on rock shaft 99. This rock shaft also carries arms 100, which 30 are illustrated in Figure 1, in any intermediate position from which they oscillate in both directions during the operation of the device. These arms 100 will correspond in 35 number to the number of cutters to be actuated. For while I have illustrated and described only two cutters side by side, it will be obvious that a machine of this character can be extended from front to rear to operate 40 simultaneously upon as many webs as may be desired. The showing of means for operating on two webs will be understood to exemplify the fact that a plurality of webs 45 may be treated with a machine of this type as readily as a single web may be acted upon.

The arms 100 on rock shaft 99 are provided at their upper extremities with clevises 101, whereby the adjustable links 102 are pivotally 50 connected thereto. Each of the links includes a barrel 102' internally threaded to receive right and left hand threaded members 103 and 104 (see Fig. 3). This arrangement permits of the ready adjustment of the length of 55 the links. The end of each link remote from its pivotal connection with the clevises of arms 100 is connected pivotally with one of the slides 17 which carry the shear bars 25. The arrangement is such that the rotation of 60 shaft 94 causes the oscillation of shaft 99 and the corresponding reciprocation of the slides carrying the shear bar. By means of disks 75' and 80' the relative timing between the 65 shear bars and the remainder of the machine may be varied without altering the synchro-

nization of the parts. By interchanging gear 95 with other gears of different ratios relative to gear 14, and by adjusting the intermediate gear 90 accordingly, the synchronization of shaft 94 with the remainder of 70 the machine may be altered to vary the length of sheet which will be severed during the forward and rear strokes of the shear bar. Independent adjustments of the shear bars may be made when necessary by means of the 75 adjustable lengths 102.

The operation of the machine has already been fully described, and I have also described means for making adjustments in the driving connections to vary the relative positions of 80 different elements acting upon the paper, and also to vary the timing or synchronization of such elements. As illustrated in the accompanying drawings, gear 95 has a ratio of two to one as compared with the gear 14 from which it is driven. In other words, gear 95 will make one rotation for each two rotations of rolls 8 and 9. As a result of this proportion, and as a further result of the fact that the shear bar 25 severs a blank from 90 the web twice during each complete cycle, it will be obvious that with the gear 95 as illustrated each blank will have a length equal to the circumference of rolls 8 or 9. By substituting for gear 95 a gear of a different ratio 95 with respect to gear 14, it is possible to cut from the longitudinally folded web portion 7 a blank having a length lesser or greater than the circumference of roll 8. The length of the blank will always be one-half of the circumference of gear 95, due to the fact that the shear bar 25 makes two cutting strokes for each rotation of said gear. Consequently, the operator can conveniently determine the size of gear 95 by selecting a gear which has 100 a circumference equal to twice the length of the desired blank. If such a substitution be made, it is obvious that a corresponding substitution will have to be made in the gears through which the tucking blade is operated. 105 Otherwise, the shortened blank would pass the tucking blade to a greater proportionate extent with each successive cycle of operation. In order to ensure that the tucking blade will strike the same relative portion of each successive blank acted upon by it, the several 110 gears 71, 72, and 73 are provided to correspond in their ratios with gear 60 to the ratio adopted between gear 95 and gear 14. Note that a corresponding rather than an identical ratio 115 is used. The tucking blade completes but one operation in its cycle of movement, whereas the shear bar completes two operations in its 120 cycle of movement. Thus, the circumference of that gear 71, 72, or 73 which is selected on 125 driven shaft 70 will always be equal to the length of the desired sheet in order that the tucker may operate once during each rotation of the chosen gear.

The adjustment made possible by the use 130

of disks 76 and 80 provides for a change in the relative position of the tucker so that a greater or lesser length of the blank may be allowed to pass the blade before being acted upon thereby. Thus, the blank may either be folded in its exact center or to one side of the center as may be desired, and consequently, it is possible to secure a wide variety of folds on a machine of this character. Note particularly that a change in the relative position of the tucker blade, such as may be accomplished by adjustment of plate or disk 80, has no effect upon the synchronization of the parts and permits them to continue to operate with the same timing as that previously employed. In other words, the number of operations performed in a complete rotation of the driving gear will be constant, although the point of the cycle at which each operation is performed may be adjusted.

I claim:

1. In a device of the character described, the combination with web feeding mechanism, of a pair of relatively stationary shear bars associated with said mechanism and positioned to receive between them a web acted upon by said mechanism, a reciprocable shear bar associated with said stationary shear bars and adapted to interact with each of said stationary shear bars in the course of each complete reciprocation, and driving connections for said feeding mechanism and said reciprocable shear bar, said connections including change speed mechanism operable to control the relative rates of operation of said feeding mechanism and shear bar.
2. In a device of the character described, the combination with a rotary feeding device, of a rotary driving member operatively con-

nected therewith, a driven member rotatable 40 concentrically with the driving member and rotatably adjustable with reference thereto, and a web cutter connected to be operated from said driven member and disposed to act upon material fed by said feeding device. 45

3. In a device of the character described, the combination with a rotary web feeder, of a rotary driving member, motion transmitting connections between said feeder and driving member and comprising with said driving 50 member rate changing mechanism, a driven member rotatable in axial alignment with the driving member and rotatably adjustable with reference thereto, and a web cutter connected to be operated from said driven member in association with said feeder to sever blanks from webs acted upon by said feeder. 55

4. In a device of the character described, a web cutting device comprising a bed member providing a longitudinally extending 60 downwardly tapering bearing surface, a shear bar reciprocable on said surface, and a pair of relatively stationary, closely spaced shearing surfaces positioned for co-operation with said bar. 65

5. In a device of the character described, a web shearing mechanism comprising a bed member having longitudinally extending, downwardly tapering bearing surfaces, a 70 head reciprocable on said surfaces and provided with a transversely extending shear bar, means for adjusting one of said bearing surfaces toward the other bearing surface, whereby to take up wear, and a plate confining said head upon said surfaces and provided with a transverse slot having margins 75 co-operative with said bar.

ALDEN HUDSON.
